Attorney, Agent, or Firm—Mark C. Jacobs, Esq.

[57] CLAIM

The ornamental design for a cutting board food retention attachment, as shown and described.

DESCRIPTION

FIG. 1 is a perspective view of the first embodiment of the cutting board food retention attachment;

FIG. 2 is a top plan view thereof;

FIG. 3 is a front elevational view of this first embodiment.

FIG. 4 is a rear elevational view thereof;

FIG. 5 is a bottom plan view thereof;

FIG. 6 is a right side elevation view thereof;

FIG. 7 is a left side elevation view thereof, the broken line showing is for illustrative purposes only and forms no part of the claimed design;

FIG. 8 is a perspective view of a second embodiment of the cutting board food retention attachment, the top and bottom views are the same as shown in FIGS. 2 and 5 respectively;

FIG. 9 is an enlarged partial perspective view of one of the attachment means to a cutting board; and,

FIG. 10 is a view taken along line 10—10 of FIG. 9.
